UNITED STATES PATENT OFFICE.

RANDALL M. PATTERSON, OF WEATHERFORD, OKLAHOMA TERRITORY.

ACETYLENE-GAS MACHINE.

No. 831,519.

Specification of Letters Patent.

Patented Sept. 18, 1906.

Application filed August 21, 1905. Serial No. 275,027.

To all whom it may concern:

Be it known that I, RANDALL M. PATTERSON, a citizen of the United States, residing at Weatherford, in the county of Custer and Territory of Oklahoma, have invented a certain new and useful Acetylene-Gas Machine, of which the following is a specification, reference being had therein to the accompanying drawings.

10 This invention relates to acetylene-gas machines, and particularly to that class of machines known as "carbid-feed" generators, the primary object of the invention being to provide a simple, economical, and reliable acetylene-gas generator which will fulfil the requirements of insurance companies in point of safety.

One of the main objects of the invention is to provide means for intermittently discharging a predetermined amount of carbid into the water, said means being entirely automatic in action and the amount or charge of carbid being accurately measured previous to the same being deposited in the water.

25 A further object of the invention is to provide a machine of such construction that the several parts thereof may be easily disassociated for cleaning, repairing, and refilling or charging.

30 With the above and other objects in view, the nature of which will more fully appear as the description proceeds, the invention consists in the novel constructions, combination, and arrangement of parts, as herein fully described, illustrated, and claimed.

35 In the accompanying drawings, forming part of this application, Figure 1 is a vertical sectional view of an acetylene-gas machine embodying the present invention. Fig. 2 is an enlarged vertical sectional view of the carbid-holder, showing the carbid measuring and discharging mechanism. Fig. 3 is a bottom plan view of the carbid-holder, showing the carbid-valve and the operating mechanism therefor.

45 Like reference-numerals designate corresponding parts in all figures of the drawings.

The generator contemplated in this invention comprises an outer can or vessel 1 of suitable height and diameter, according to the capacity of the machine, and 2 represents the inner can or shell, which extends from a point near the top of the outer can downward until it meets and connects with an an-

55 nular floor 3, the latter, together with the inner can, being supported on brackets 4, secured to the inside of the outer can, as shown. Between the outer and inner cans 1 and 2 an annular water-seal space is left, in which is received the lower portion of the 60 gas-bell 5, the latter fitting loosely around the inner can and being closed at the top, where it is provided with a vent-cock 6, which is normally closed. The outer can 1 is provided with a slanting bottom 7, and a 65 draw-off cock 8 is located in the side of the can adjacent to the lowest portion of the slanting bottom to provide for drawing off the water from the can preparatory to replenishing the same.

70 The carbid-holder 9 is removably mounted in the upper portion of the inner can 2, being supported on brackets 10, secured to the inner can, as shown, and is thus adapted to be taken out of the machine after the gas-bell 75 has been lifted off, thus greatly facilitating the recharging of the machine. This carbid-holder is provided with a flanged top or cover 11 and has an inverted-cone-shaped bottom 12, with a central discharge-opening 80 13 disposed above the water-level in the inner can. Beneath the cone-shaped bottom 12 is a horizontal bottom plate 14, to the bottom of which is secured a measuring cup or chamber 15, adapted to contain a certain 85 amount of carbid sufficient when deposited in the water to generate gas enough to nearly fill the bell 5, causing the latter to rise. It will be noted that the discharge-opening is somewhat smaller than the measuring-cup to 90 prevent the carbid from congesting in the discharge-orifice.

95 The carbid at the point of discharge is loosened up by means of an agitator consisting of a rod or stem 16, having a carbid-lifting crook at its lower end, while the upper end thereof extends through the top of the holder to be acted upon and depressed by the gas-bell as the latter descends just before a new charge of carbid is to be dropped into 100 the water. The rod or stem 16 passes through a tube or guide 17, supported centrally within the carbid-holder by means of brackets 18, and said rod or stem is normally pressed upward and upheld by means of a 105 spring 19, which encircles the stem within the tube 17 and bears beneath a pin or shoulder 20 on the rod or stem.

Extending under the cup or measuring-receptacle 15 is a valve or plate 21, which closes the lower end of said cup and retains the carbid therein preparatory to its discharge. The valve or plate 21 is carried by an arm or brace 22, which at its outer end is mounted on the lower end of a vertically-adjustable rod or stem 23. This rod passes upward through a tubular guide 24, supported by brackets 25, and the upper end of such rod is threaded and provided with a nut 26, which bears on the upper end of the tubular guide and renders the rod 23 adjustable up or down for the purpose of bringing the valve or plate 21 into proper relation to the discharge-orifice of the cup 15. Said rod or stem 23 also forms a pivot or journal about which the valve or plate 21 is adapted to turn for covering and uncovering the cup 15.

20 The operating mechanism for the valve or plate 21 comprises a rock-shaft 27, mounted in bearings 28 on the bottom plate 14. This shaft is provided at one end with a crank-arm 29, to which is attached one end of a chain 30, the other end of which is connected to the valve-plate 21. At the opposite end the shaft 27 has another crank-arm 31, to which is connected the lower end of a rod 32, the latter extending upward through one or more guides 33 and above the carbid-holder, so as to be depressed by the gas-bell as the latter descends. Thus when the bell approaches the lower limit of its movement it depresses the rod 32, rocks the shaft 27, 35 and moves the valve from under the cup 15, allowing a charge of carbid to fall into the water. As soon as the gas is generated the bell rises again, releasing the valve-operating connections, whereupon the valve is returned to its closed position by means of a retracting-spring 34, one end of which is connected to the valve and the other end to the body of the carbid-holder.

35 designates a gas-receiving pipe extending vertically within the inner can or shell to a point near the top of the latter. The lower end of this pipe is coupled to a horizontal pipe 36, one end of which extends into a condensation-box 37, secured to one 40 side of the outer can 1 and provided with a nipple 38 for the attachment of the service-pipe for conducting the gas to the burners. Said box is also provided with a drain-cock 39 to draw off the residuum. The other end 45 of the pipe 36 passes out through the side of the can 1 and has a vertical extension 40, supported by one or more brackets 41 on the can and reaching to a suitable point above the top of the can, where it is provided with 50 a safety valve or cock 42, the latter having a crank-arm 43 projecting therefrom into the path of the gas-bell, so that in case there is an excess of gas within the bell the latter will in its upward movement come in contact

with the crank-arm 43, causing the latter to open the valve or cock 42 and liberate the gas, thus preventing the bell from being lifted out of the water seal and displaced.

Having described the invention, I claim as new—

1. In an acetylene-gas machine, the combination of a can, a gas-bell movable up and down therein, and a removable carbid-holder in said can carrying a measuring-cup open at the bottom, and a pivoted and swinging plate-valve also carried by said holder and movable edgewise across the bottom of said cup for closing the same, and valve-operating means carried by and removable with the carbid-holder and embodying a rod having connection with the valve and extending upward alongside the carbid-holder and arranged to be operated by the gas-bell.

2. In an acetylene-gas machine, the combination of a can, a gas-bell movable up and down therein, and a removable carbid-holder comprising a measuring-cup open at the bottom, a pivoted and swinging plate-valve movable edgewise across the bottom of said cup for closing the same, valve-operating means carried by and removable with the carbid-holder and embodying a rod having connection with the valve and extending upward along the outside of the carbid-holder and arranged to be operated by the gas-bell, and a retracting-spring for returning said valve to its closed position.

3. In an acetylene-gas machine, the combination of a can, a gas-bell movable up and down therein, and a removable carbid-holder comprising a measuring-cup open at the bottom, a pivoted and swinging plate-valve movable edgewise across the bottom of said cup for closing the same, valve-operating means carried by and removable with the carbid-holder and embodying a rock-shaft, a connection leading therefrom to the valve, and a rod having connection with the rock-shaft extending upward along the outside of the carbid-holder and arranged to be operated by the gas-bell.

4. In an acetylene-gas machine, the combination of a can, a gas-bell movable up and down therein, and a carbid-holder removable from the can and comprising a measuring-cup carried by said holder and open at the bottom, a plate-valve mounted on a vertical pivot to move edgewise across the bottom of the measuring-cup, means for operating said valve, and means for adjusting said valve up and down in a plane parallel to the axis of its pivot and maintaining such adjustment, the valve operating and adjusting mechanism being carried by and removable with the carbid-holder.

5. In an acetylene-gas machine, the combination of a can, a gas-bell movable up and down therein, and a carbid-holder remov-

able from said can and comprising a measuring-cup open at the bottom, a pivoted and swinging plate - valve movable edgewise across the bottom of the cup, means for operating said valve, a vertical rod forming the pivot of the valve and adjustable endwise for positioning the valve with respect to the measuring-cup, and means for adjusting and holding said rod, the valve operating and | adjusting mechanism being carried by and removable with the carbid-holder.

In testimony whereof I affix my signature in presence of two witnesses.

RANDALL M. PATTERSON.
